[57] CLAIM

The ornamental design for a plant stand, substantially as shown.

DESCRIPTION

FIG. 1 is a perspective view of a plant stand, showing my new design;

FIG. 2 is a front elevational view thereof, drawn to a larger scale;

FIG. 3 is a side elevational view thereof, as viewed from the left of FIG. 2;

FIG. 4 is a rear elevational view thereof;

FIG. 5 is a side elevational view thereof, as viewed from the right of FIG. 2;

FIG. 6 is a top plan view thereof, and

FIG. 7 is a sectional view, corresponding to the line 7—7 of FIG. 2.

FIG. 1.

FIG. 2.

FIG.5.

FIG.6.

FIG.7.
